STENCIL PRINTING MACHINE

Stephen L. Mershon, Springfield, Pa.

Application July 12, 1935, Serial No. 30,973

9 Claims. (Cl. 101—116)

My invention relates to stencil printing machines and more particularly to those machines wherein a stencil and a plate on which is supported the sheet to be printed are delivered to and passed between a pair of platen rollers, one of which is an inking roller in contact with the stencil and after passing between said rollers and imprinting the matter of the stencil on the card, or sheet between the stencil and the plate, the said stencil plate and printed sheet are automatically returned to substantially the point or position in which they were at the beginning of the operation.

Heretofore, in this type of machine, the said plate on which was placed the card or sheet to be printed slid in one track or guideway, and the stencil was similarly slidable in a separate runway or guideway immediately above the guideway first mentioned, independently of the plate. The stencil and sheet to be printed were not in substantial contact until they were drawn between the platen rollers. As a result of this the card or sheet to be printed was often not in proper registry with the stencil. In moving the plate and the stencil into proper position to be engaged by the rollers, the card or sheet was likely to be displaced on the plate and out of proper registry with the stencil.

It is an object of the present invention to overcome these difficulties by attaching the stencil to the plate in such a manner that whenever the stencil is positioned on the plate it is always in the same position so far as registration with respect to the plate is concerned. The stencil may be hingedly or otherwise flexibly secured or movably secured to the plate, but whenever it is applied to the plate with a sheet or card to be printed between it and the plate, the stencil is always in exactly the same position with respect to the plate.

A further object of this invention is to secure the plate and stencil together in such a manner than the stencil may be raised to permit of the insertion and proper placement and removal of the sheet and to make of the plate, the stencil and the sheet to be printed a unit construction to be manually moved up into position to be engaged by the platen rollers.

A further object of this invention is to dispense with the separate guideway for the stencil by supporting the stencil directly on the plate and in an invariable position with respect to the plate.

A further object of this invention is to provide a stencil and the reciprocating plate, upon which

the sheet or card to be printed is supported, with means which accurately position the stencil in identical relationship with respect to the plate.

A further object of this invention is to provide a unitary construction of plate and stencil whereby the sheet to be printed is immovably held in its proper position on the plate by the weight of the stencil lying thereon.

Further objects of this invention will appear in the specification and claims below.

In the drawings forming a part of this specification and in which the same reference characters are employed throughout the various views to designate the same parts,

Fig. 1 is a plan view of the essentials of a mechanism for stencil printing with my improved unitary combined plate and stencil manually moved in the guideway up to starting position, the forward ends thereof being between the platen rollers.

Fig. 2 is a longitudinal cross-sectional view of the same.

Fig. 3 is a view similar to Fig. 2 showing the position of the parts at the completion of the cycle of operation.

Fig. 4 is a side elevational view of the gearing by means of which the platen rollers are rotated in unison.

Fig. 5 is a plan view similar to Fig. 1 of a modification of the invention.

Fig. 6 is a longitudinal vertical sectional view on the line 5—5 of Fig. 5.

In Figs. 1 to 4 is illustrated that part of a stencil printing machine to which this invention has particular reference. Thus the platen rollers 1 and 2 may be and preferably are of standard design and equipment, the upper roller 1 being the inking roller and the lower roller 2 being preferably a metal roller. The upper inking roller is preferably provided with a yielding surface 3 of rubber or other suitable material. Both rollers are preferably mutilated so that when they are in their stationary position, as shown in Fig. 3, there is a clear open space between them. The rollers are of the same peripheral diameter and they are geared together to turn in unison by spur gears 4—4, one secured to the upper roller shaft 5 and the other to the lower roller shafts 6. The framework of the machine is indicated by the upright 7 in which the shafts 5 and 6 are journaled, the upright 8 at the front of the machine, the parallel rails 9, 10 mounted on the uprights 7 and 8 and the cross-bars 11 and 12 tying the rails together.

The inner sides of the rails 9 and 10 are each 55

provided with a groove 13 forming a track throughout the length of the rails in which the metal plate 14 can be freely slid manually when the rollers are in the position shown in Fig. 3 or 5 automatically by the rollers as shown in Fig. 2 wherein the platen rollers have just started to rotate and are impelling the plate and stencil rearwardly. The plate 14 may be provided with a handle 15 to facilitate the proper positioning 10 of the plate for the commencement of the printing operation.

In the construction illustrated in Figs. 1 to 3 the stencil 16 is permanently connected to the rear end of the plate 14 by hinges 17. These 15 hinges 17 are preferably spaced apart as widely as possible as will be referred to again below. The stencil per se consists of a thin metal rectangular frame 18 turned over along the front and back edges to form channels 18' and 18'' into 20 which the removable stencil card or sheet 19 is fitted. To firmly retain the removable stencil sheet 19 to the frame 18 I may employ the usual flexible resilient metal locking frame 20.

On the upper side of each rail are two upwardly 25 extending lugs 21 and 22 between each pair of which extends a guide rod 23 and on each rod is a block 24, slideable on its rod 23 and having an inwardly projecting finger or shoulder 24' said fingers extending into the path of the movement 30 of said plate 14. Each block is normally held squarely against its lug 21, but yieldingly, by a coiled spring 25, one end of a spring being attached to a block 24 and the other end to a rail 35 of the frame. These blocks 24 with their inwardly extending fingers 24' are in effect yielding stops against which the rear end of the plate 14, or the hinges 17 connecting the plate with the frame, abut when the plate and stencil have been manually pushed forwardly to a position between 40 the rollers, the rollers at that time being in the position shown in Fig. 3.

When the plate and stencil unit is so manually positioned between the rollers and against the stop fingers 24' power is applied to the rollers, and 45 they are given one complete revolution and then their motion is stopped. It is not deemed necessary herein to illustrate the clutch mechanism for stopping the rotation of the rollers, after one complete rotation, since any one of a number of 50 those well known throw-out clutch mechanisms could be mounted in the clutch housing 7' for the purpose, and because, in fact, the mechanism might be operated by hand by a crank mounted on either of the roller shafts 5 or 6.

55 But when the rollers begin to turn they draw rearwardly between them the plate and stencil which in turn push the blocks 24 rearwardly on their guide rods 23 against the tension of the springs 25. When the platen rollers 1 and 2 have 60 completed their revolution and come to rest again in the position shown in Fig. 3, the springs 25 come into operation and draw the plate 14 and stencil 16 back through the space between the rollers toward the front of the machine until the blocks 24 re-engage their respective stop lugs 21 as shown in Fig. 3.

I have shown a spring latch 26 mounted on 70 the top of one of the rails on a vertical pivot pin 27, the latch being movable in a clockwise direction but not movable in an anticlockwise direction beyond the position shown in Fig. 1 by reason of the engagement to a lug 28 on the latch 26 with a rigid stop pin 29. The spring 30 normally holds this latch 26 in the position shown in Fig. 1.

The stencil frame 18 is preferably provided with a little upwardly directed lug 31 and the latch 26 normally extends into the path of this lug 31. When a card 32 is placed between the plate 14 and the unit is being manually advanced to bring 5 them into starting position, the lug 31 strikes the forward side of the said latch 26 and rotates it in a clockwise direction against the tension of the spring 30, and, after the lug 31 passes to the rear of the latch 26, the spring 30 snaps it back 10 to normal position against the lug 28.

When, however, a printing cycle has been completed and the plate 14 and stencil 16 together come to rest near the front of the machine, the operator may grasp the handle 15 and 15 draw the plate further rearwardly until the lug 26 engages the rear side of the latch 26 which cannot move further in an anticlockwise direction with the result that the stencil is rotated on its hinges 17 and is lifted well above the plate (see 20 Fig. 3) in order to facilitate the removal of the now printed sheet 32 and the substitution therefor of a fresh sheet to be printed during the next printing cycle.

The upper face of the plate 14 may have a thin 25 guide strip 33 against which the side 32' of the card or sheet 32 to be printed may abut, and the plate 14 may have a scratch or marking 34. The card or sheet 32 is manually placed on the plate 14, against the guide 33 and in the position 30 indicated by the markings 34, the stencil 16 being lifted on its hinges 17 for the purpose. The stencil 16 is then turned on its hinges down flat upon the plate and the sheet to be printed. The sheet 32 is thus clamped between the plate and 35 the stencil. The weight of the stencil and its frame is amply sufficient to tightly hold the sheet immovable against the plate. The operator then grasps the handle 15 slides the plate and stencil 40 forwardly until the hinges 17 engage the fingers 24' and should the stencil sharply engage the stop fingers 24' and thus be suddenly brought to rest, the card or sheet 32 will not slip with respect to the stencil 16 or the plate 14, due to its 45 momentum, for it is firmly clamped between the plate and the stencil. The operator then applies the power which rotates the rollers for one complete revolution and thus impel the plate and stencil through the machine to the rear thereof 50 and during this action the inking roller presses the stencil sheet firmly against the card or sheet 32 and effects a printing thereon of the data carried by the stencil. When brought back to the front of the machine by the springs 25, the drawing of the plate a little further, manually, 55 by the handle 15, effects an automatic lifting of the stencil frame and stencil carried thereby giving access to the upper side of the plate.

It will now be seen that in the practice of my 60 invention, that it is not necessary to provide the rails 9 and 10 each with two guideways one for the plate and one for the stencil as has heretofore been done. The single guideway for the plate suffices for the operation. Moreover, the 65 stencil when thus permanently hinged to the frame when flat will always be in registry with the identical part of the plate. The stencil cannot change its position with respect to the plate so far as registration is concerned.

Moreover, the plate 14 bearing the sheet or 70 card 32 and the stencil 16 hinged thereto form a unitary construction. They move as a unit with respect to the rails whether impelled manually by the handle or automatically by the rollers. 75 There is no slip or relative movement of the

stencil with respect to the plate or of the sheet to either.

In the modifications shown in Figs. 5 and 6 the lower platen roller 2, the uprights 7 and 8, the rails 9 and 10 with the cross bars 11 and 12, the latter being provided with grooves or slide ways 13 are of the construction above described in connection with Figs. 1 to 3.

But the upper inking platen roller 1^a is hollow to provide a chamber 35 constituting an ink reservoir. The wall of the upper roller is provided with perforations 36 through which the ink may be distributed to a yielding ink absorptive pad 3^a over which is smoothly fitted the removable stencil sheet 19^a secured thereto by clips or clamps 37.

The roller 1^a may be replenished with ink from time to time through the opening through the wall thereof closed by the plug 38.

The plate 14^a is substantially like that shown in the previously described construction except that the removable stencil sheet 19^a is not connected thereto by hinges. Instead, the upper roller shaft 5 is provided with a pair of mutilated gears 39, one at each end of the roller 1^a, and adapted to intermittently mesh with racks 40 rigidly secured to the plate 14^a adjacent opposite side edges thereof.

The rollers 1^a and 2 are preferably geared together to rotate in unison by means of gearing 4-4 like that shown in Fig. 4.

When the machine is not operating the flat faces of the two rollers 1^a and 2 are parallel providing a space between the rollers for the insertion of the rear end of the plate 14^a in order that it may be advanced into engagement with the fingers 24' of the blocks 24 by means of which the plate 14^a is correctly positioned for starting. Upon the application of power to the platen rollers the first tooth of each of the gears 38 will mesh between the same teeth of the rack 40 every time the printing cycle is started and by this gearing the stencil is thus accurately and invariably connected to the plate 14^a and moves therewith to impart the impression of the stencil to the card 32 lying on the plate 14^a. When the platen rollers have made one complete revolution they are stopped with the flat surfaces of the rollers 1^a and 2 parallel, whereupon the plate 14^a is returned to its starting position by the springs 25 drawing the blocks 24 on their guide rods 23 rearwardly against the stop lugs on the rails 9 and 10. The printed sheet may now be lifted from the plate 14^a and a new sheet accurately placed thereon.

It is often desirable to print parts only of the matter cut into the stencil as in making up index cards from different parts of the matter cut into the stencil.

Some of the index cards to be thus made may contain printed matter and the data on the stencil may be for insertion in blank spaces provided therefor on the printed cards.

In Fig. 1 I have indicated the complete data cut into the stencil by the three columns 41, 42 and 43 of dotted lines.

For example, if a part only of column 31, a lesser part of column 42 and none of column 43 are to appear on the index cards 32 to be printed therefrom, then preferably a sheet of blotting paper may be accurately cut to the shape 44 indicated in dot-and-dash lines in Fig. 1 and placed upon the card 32 before the stencil is lowered to lie thereover.

When now the unitary construction comprising the plate 14, the stencil 16, the card 32 and the blotter are now run between the platen rollers 1-2, only that part of the data on the stencil which has not been masked out by the blotter, 5 will appear on the card 32.

It will also be plain that a portion of the data on the stencil might be for transference to a printed sheet which is longer than the plate 14. It is for this reason that I locate the hinges 17 10 close to the side edges of the plate so that the sheet might project rearwardly beyond and between the hinges.

My device is also well adapted for making cards or coupons for piecework. The main stencil 15 may contain all the prices to be paid for each operation and the other data may appear as printed matter on the cards, the prices on the stencil being for insertion on the cards opposite the appropriate printed notation for the particular 20 operation. These piecework cards may be perforated for separation and for distribution to the workmen, each of whom, at the close of the day, turns in as many of the coupons as corresponds to the number of times he has performed that 25 operation during the day. It will be appreciated that since the price of these various operations may vary greatly, it is exceedingly important that the matter transferred to the cards from the stencil appears in is correct position on the 30 printed card.

This kind of work is relatively easy when my herein described invention is employed, because the registration of the stencil with the identic part of the plate is substantially perfect and because once the stencil has been lowered to lie flat on the card the likelihood of any slippage of the card on the plate 14 is substantially eliminated. Once the card has been properly positioned on the plate and clamped between the 40 plate and the stencil, the registration of the matter to be transferred from the stencil to the proper position on the card is insured.

In the drawings, the platen rollers are substantially alike; they are of the same diameter 45 and both have flattened sides which are parallel when the rollers are stopped to provide a clear space between the rollers for the insertion of the plate and stencil. At least one of these rollers should be a flattened sector and preferably the 50 upper inking roller 1 in order that the stencil may be inserted between the rollers without contacting with the inky surface of the upper roller. It is not so important that the lower roller be a sector although by making it flattened or mutilated ample space is provided for the ready insertion of the stencil and plate between the rollers prior to the printing operation.

Having thus described my invention, what I claim and desire to protect by Letters Patent of 60 the United States is:

1. In a stencil printing machine, a sheet supporting plate, a frame providing a guideway for the opposite side edges of said plate, a pair of co-acting rotatable rollers mounted in said frame, 65 each of said rollers having a platen sector and having a portion removed to provide a free space between said rollers in the stationary position thereof, said plate being manually movable in said guideways into said space when said rollers 70 are stationary, a yielding stop to accurately position the forward edge of said plate with respect to said rollers, a stencil movable with said plate with the sheet to be printed between said stencil and said plate, the platen sectors of said rollers re- 75

5. respectively engaging said stencil and said plate to advance the same to effect the printing operation, and means to connect said stencil to said plate and to unvariably position said stencil with respect to said plate to maintain absolute registration of said stencil with said plate during the printing operation.
2. In a stencil printing machine, a sheet supporting plate, a frame providing a guideway for said plate, a pair of simultaneously operable co-acting rollers having platen sectors and substantially parallel portions providing a free space between said rollers when said rollers are stationary, means to accurately position the forward edge of said plate with respect to said rollers, and a stencil hinged to said plate and movable there-with between said rollers, the platen sectors of said rollers respectively engaging said stencil and said plate to advance the same to effect the printing operation.
3. In a stencil printing machine, a sheet supporting plate, a frame providing a guideway for said plate, a pair of simultaneously operable co-acting rollers having platen sectors and substantially parallel portions providing a free space between said rollers when said rollers are stationary, means to accurately position the forward edge of said plate with respect to said rollers, a stencil hinged to said plate for movement with the plate, the platen sectors of said rollers respectively engaging said stencil and said plate to advance the same to effect the printing operation, and means to automatically lift said stencil from said plate on its hinge, after the printing operation has been completed.
4. In a stencil printing machine, a sheet supporting plate, guides along which said plate is slidable, a pair of platen sectors geared together for rotation simultaneously in opposite directions, said plate being insertable in the space between said sectors when said sectors are stationary, a stencil, means for connecting said stencil to said plate and for positioning said stencil in unvarying registration with said plate for every printing operation, yielding means for positioning said plate with respect to said sectors, said sectors respectively engaging said stencil and said plate and being movable through one complete revolution to feed said plate and stencil through said rollers and to press said stencil firmly against a sheet between said stencil and said plate, said yielding means being operative to draw said plate and stencil back to the front of the machine after said printing operation.
5. In a stencil printing machine, a sheet supporting plate, a pair of platen sectors geared together for rotation simultaneously in opposite directions, said plate being insertable in the space between said sectors when said sectors are stationary, a stencil, means for connecting said stencil to said plate and for positioning said stencil in unvarying registration with said plate for every printing operation, yielding means for positioning said plate with respect to said sectors, said sectors respectively engaging said stencil

and said plate and being movable through one complete revolution to feed said plate and stencil through said rollers and to press said stencil firmly against a sheet between said stencil and said plate, said yielding means being operative to draw said plate and stencil back to the front of the machine after said printing operation, and means for automatically raising said stencil from said plate when said plate has been returned by said yielding means.

6. In a stencil printing machine, a sheet supporting plate mounted for sliding movement, a pair of rollers, one of which has a sector, each roller being normally stationary with the generally flattened surface of the sector adjacent to the other roller to provide a space therebetween for the insertion of said plate, yielding means for positioning said plate with respect to said rollers, a stencil secured to said plate in unvariable registration with said plate, said rollers respectively engaging said stencil and said plate and being movable through at least one complete rotation for advancing said plate and stencil between said rollers to the rear side of said machine, said yielding means being operative to return said plate to the front of said machine when said rollers have completed said rotation.

7. In a stencil printing machine, a flat sheet supporting plate, a pair of rollers, one of which is a platen sector normally stationary with the generally flattened surface of said sector adjacent to said other roller to provide a clear space therebetween, a guideway in which said plate is slid-able into said space, a stencil, means for hinged-ly securing said stencil to said plate and for bring-ing said stencil into identical registration with respect to said plate, the sheet to be printed being held stationary on said plate by said stencil, said rollers respectively engaging said stencil and said plate and being movable through one complete rotation for advancing said stencil and said plate to effect the printing operation, and yielding means for returning said plate and stencil to the front of said machine immediately the rotation of said rollers is completed.

8. In a stencil printing machine having a pair of rotatable platen sectors with cut away portions to provide in an initial stationary position there-of a free space therebetween, a stencil, a sheet supporting plate slidably mounted for passage between said sectors, and means for mounting said stencil in superposed position with respect to said plate for simultaneous movement with said plate between said platen sectors.

9. In a stencil printing machine, a pair of rollers having cut away portions arranged to provide a free space therebetween, a sheet receiving plate adapted to be received between said rollers, guides along which said plate is slid-able, a stencil, and means for mounting said stencil to register said stencil with said sheet receiving plate during rotation of said rolls and to remove said stencil from contact with the sheet after completion of the printing.

STEPHEN L. MERSHON. 65
